UNITED STATES PATENT OFFICE.

ALBERT PRIESTLEY, OF HALIFAX, ENGLAND.

STEAM-BOILER SETTING.

Application filed September 22, 1922. Serial No. 589,847.

To all whom it may concern:

Be it known that I, ALBERT PRIESTLEY, a subject of the King of Great Britain, residing at Halifax, in the county of York, 5 England, have invented new and useful Improvements in and Relating to Steam Boiler Settings, of which the following is a specification.

This invention consists of improved settings for steam boilers, particularly of the Lancashire and Cornish type, and my object is to effect considerable economy in fuel and increase the steam raising efficiency of the boiler by an improved construction and 15 arrangement of flues for conducting the waste heat, hot gases, or the like from the boiler furnaces or furnace to the chimney shaft. The construction of these flues greatly increases the length of flue traverse, and 20 the passage of the hot gases through the same constitute a series of heat streams which are localized and distributed over the boiler shell from the back to the front and from the front to the back thereof, the maximum heat being applied where the weight 25 and depth of water is greatest, and is gradually absorbed by the boiler until on approaching the water level or where the weight of water is least, the temperature is 30 correspondingly or proportionately less. The continued absorption of the heat of the hot gases by the boiler during their lengthened traverse through these flues, is such as to effect a substantial reduction therein before discharging into the main flue, which 35 not only increases the boiler efficiency as aforesaid, but also reduces the volume of smoke entering said flue, and the wear and tear on both flues and chimney.

According to my invention, I construct the settings so as to form a number of flues beneath and at the sides of the boiler. These flues connect the boiler furnaces or furnace with the main flue or chimney shaft, 45 and comprise a central flue leading out of the back chamber receiving the waste heat from the furnaces, towards the front of the boiler, where the hot gases therein are now divided by suitable means into two separate 50 streams, each stream passing into a flue parallel to the central flue and upon each side thereof. Each of these side flues has extensions which pass from the front to the back, and from the back to the front of the

boiler, the different levels being connected 55 by uptakes at one end or the other, as the case may be, until they eventually discharge into the main flue or chimney shaft. In this manner, it will be seen, two separate heat streams in a concentrated form are fed 60 from the central or maximum heat flue, the heat being localized and in contact with the boiler shell all the way, whilst the length of traverse is more than doubled, giving the 65 results desired.

I attain these objects by the means illustrated in the accompanying drawings, in which:—

Fig. 1 is a sectional plan view of my invention taken substantially along the line 70 1—1 of Figure 2, and showing the device applied to a Lancashire boiler; Fig. 2 is a sectional end view taken along the line 2—2 of Fig. 6; Fig. 3 is a similar view to Fig. 2 through the line 3—3 of Fig. 1 and 75 Fig. 6; Fig. 4 is a longitudinal sectional elevation of my improved boiler setting showing boiler in position thereon; Fig. 5 is a longitudinal sectional plan of my invention, through the line 5—5 of Fig. 2, 80 Fig. 6 is a vertical longitudinal sectional view; Fig. 7 is a horizontal, longitudinal sectional view of the invention.

Referring to the drawings, 1 is a Lancashire boiler, 2, 2, are the furnaces or furnace tubes thereof, whilst 3 is the back chamber or superheater chamber into which the waste heat from the said furnaces is normally discharged.

In constructing my invention, I partition 90 the flue ordinarily leading from the chamber 3 to the boiler front, into preferably three or more separate parallel flues, the central flue 5 having preferably a capacity equal to both the adjacent side flues 6, 7, which are partitioned off at this end from the chamber 3. The flue 5 leads out of the chamber 3, under the boiler 1 towards the boiler front, and the partition walls 8, 8, stop short upon approaching a conical midfeather 4 situated 95 opposite the mouth of the flue 5. The hot gas impacting upon the sloping sides of the said midfeather are divided into two separate streams which return to the back of the boiler through the flues 6, 7, forming the 100 second traverse. These flues next rise and communicate by means of uptakes 9, 9, with continuations 10, 10, running parallel along 105

- each side of the boiler, and formed substantially in the lower half of the existing side flues. The continuations or extensions 10, 10, shown more clearly at Fig. 2, are created by forming a lip 11, 11, on the side walls thereof for supporting inclined slabs, blocks, or the like 12, 12, leaning or otherwise placed in contact with the boiler shell and serving as a partition. The continuations 10, 10, upon each side return to the boiler front and form the third traverse, then they again rise and communicate by further up-takes 13, 13, with further continuations 14, 14, above the partitions 12, 12, and returning to the back of the boiler once more, form the fourth traverse, which leads directly into the main flue or chimney shaft 16. The flues are controlled in the ordinary way by the dampers 15, 15.
- 20 It will be observed, by this improved construction of setting the length of flue traversed is more than doubled, the hot gases from the furnaces are concentrated and conducted in two separate streams backwards and forwards along the boiler shell, so that when they eventually pass into the main flue, the heat therein has been comparatively utilized or substantially reduced, with the results before described.
- 25

What I claim as my invention and desire to secure by Letters Patent is:—

The combination with a Lancashire steam boiler having the normal return and superimposed side flues, of partitions dividing the return flue into three parallel flues, the center flue having a capacity equal to both the adjoining side flues and communicating with the normal superheater chamber receiving the waste heat direct from the boiler furnaces, a conical midfeather at the front of the boiler dividing the waste heat issuing from the central flue into two separate streams and directing the same into the adjoining side flues; passages connecting the said side flues with the normal side flues; partitions dividing each of the normal side flues into two superimposed flues, openings at the front of the boiler connecting the said superimposed flues, and vertically operating dampers controlling the discharge outlets therefrom into the normal main flue or chimney.

In testimony whereof I have signed my name to this specification.

ALBERT PRIESTLEY.
